UNITED STATES PATENT OFFICE

133,314

DESIGN FOR A COOKING APPARATUS

Lyonel T. Finizie, Bridgeport, Conn.

Application May 31, 1941, Serial No. 101,250

Term of patent 14 years

To all whom it may concern:

Be it known that I, Lyonel T. Finizie, a citizen of the United States, residing at Bridgeport, Fairfield County, in the State of Connecticut, have invented a new, original, and ornamental Design for a Cooking Apparatus, of which the following is a specification, reference being had to the accompanying drawing, forming a part thereof.

In the drawing—

I claim:

The ornamental design for a cooking apparatus, as shown.

LYONEL T. FINIZIE.
